UNITED STATES PATENT OFFICE

HARLEY M. PURDY, OF WABASH, INDIANA

SPRING-PRESSED WEATHER STRIP AND ITS SPRING-PRESSED ACTUATOR

Application filed May 28, 1930. Serial No. 456,503.

This invention relates to double doors, and especially to an astragal or spring pressed weather strip and its spring pressed actuator.

One object of the invention is to eliminate difficulties encountered with the ordinary astragal over the crack or opening between two door-members of a double door, where the astragal or weather strip is fixed on one of the door-members, and where the door-member that has the astragal can not be closed while the door-member having no astragal is closed. In such ordinary construction, the astragal is likely to be broken or defaced by striking or being struck by a bolt or latch of the lock of the door.

Another object is to provide a double door with an astragal having yielding means to hold it out of the way of the door-member which has no astragal thereon.

Another object is to provide an effective spring-pressed means to automatically press the astragal in its weather-excluding position and to hold the door-members against rattling in consequence of the wind blowing against them.

Other objects and important features are pointed out or implied in the following description, in connection with the accompanying drawings in which:

Fig. 1 is an elevation of a double door provided with my invention, as viewed from the interior of a room closed thereby, the middle part of the door-frame, door and astragal being broken out, and a part of the threshold being shown in section.

Fig. 2 is an elevation showing the door-frame from the opposite side or outside, a part of the frame and threshold being broken off, parts of the threshold being in section, and the door-members being open and having their middle parts broken out.

Fig. 3 is a horizontal sectional view, the section being taken along line 3—3 of Fig. 1.

Fig. 4 is a view similar to Fig. 3, except the securing bolt being omitted, the astragal-carrying door-member being open, as shown in full lines and in broken lines, and a part of the door-frame and threshold being broken off.

Fig. 5 is a top plan view of the lower casing-member and the spring-pressed cam that pushes the astragal into its closed position shown in Figs. 1 and 3, a part of this cam or pusher being shown in section.

Fig. 6 is an inverted plan view of the cover of the casing-member shown in Fig. 5.

Fig. 7 is a view similar to Fig. 6, but showing a modified form of the spring-pressed pusher or cam, one of the two springs being omitted to show the bosses or spring-retainers.

Referring to these drawings in detail, in which similar reference numerals and letters refer to similar parts in the several views, the invention will now be described in detail as follows:

The doors or door-members A and B, the door-frame C, and the hinges D may be of any usual or preferred construction, materials and dimensions, and any preferred and proper kind of fastening means may be provided for the door-members. Slide bolts E are here shown as the door-fastening means, and of course they can be duplicated on the door-member A, though not here shown.

An astragal or weather-strip 10 is mounted on hinges 11 on the door-member B and covers the crack or slot a when the doorway is closed by the door-members, but when the door-member B is opened, the springs 12, of the hinges 11, swing the astragal to the positions shown in Fig. 4, where it is out of the path of the door-member A, so the latter can be opened and closed without interference with the astragal, and without danger of injuring the latter.

An actuating device such as shown in Figs. 5 and 6, when assembled, is mounted on the upper beam of the door-frame, and a similar device is mounted on the lower beam or door-sill, an opening 13 being provided in the threshold 14 to receive this lower actuator, so the top of the latter is substantially even with the top of the threshold. The opening 13 also provides a clearance for the astragal to move into and out of engagement with the lower actuator.

The actuating devices, or actuators, are

indicated at 15, in their entirety, and will now be described in detail as follows:

A lower casing-member 16 and an upper casing member 17 are united by a bolt or fastening member 18, and provided with screw-holes thru which screws 19 may extend for holding them in place on the door-frame. A cam or pushing member 20 is provided with an elongated opening 21 thru which the securing member 18 extends for permitting a limited sliding movement of the member 20 while securing it in the casing and in proper relation to the astragal. The pushing member has an arcuate or concave cam-face 22 against which an end portion of the astragal strikes when the door-member B is swung to its closing position, as illustrated by the broken lines in Fig. 4. As the door-member B is forced to its fully closed position, the cam-face 22 automatically turns it against the pressure of its springs 12 until its weather-excluding surface lies flat against the inner edges of the door-members, provided the member A is also closed, and is pushed thereagainst by springs 23 which are suitably held within the casing. The pressure of these springs also serves to hold the door-members pressed against their fastening means so they will not rattle as the wind blows against them. Moreover, even if considerable wear should result from long use of this device, the spring-pressed device 15 will compensate for such wear, so the astragal will always be caused to effectively close the crack between the door-members.

In the modified form of device shown in Fig. 7, the parts 16a and 20a may be cheaply and easily formed of blanks of sheet metal, and the same is true of the cover (not shown). The springs 23a may have their ends seated around bosses 15b and 20b formed by punching and depressing the side opposite thereto.

A rubber weather-strip 24 is shown in Figs. 2 and 3, for closing the opening at the bottom of the door, and if desirable, this can be wide enough to cover the lower actuator 15 or 15a; but I do not claim this as essential or a part of my invention, except in a broad sense. Of course the free end of the strip 24 will yield to the weather strip or astragal 10 when moving into the weather-excluding position.

Although I have described this form of my invention specifically, I have no intention of limiting my patent protection to these exact details of construction and arrangement, for the invention is susceptible of numerous changes within the scope of the inventive ideas, as implied and claimed.

The ends of the astragal may be provided

with any suitable kind of ferrule or band 25 of metal or other suitable material to contact with the cam-faces and withstand wear while rubbing against the cam-faces, and the ferrules may be held in place by screws 26 or by other appropriate means. The invention applies to windows as well as to doors.

What I claim as my invention is:

1. In a device of the character described, the combination of two elements spaced from one another, a closure member hinged on one of said elements and adapted to swing into slightly spaced relation to the second one of said elements, a weather-strip hinged on said closure member and provided with means to yieldingly hold it in a predetermined position, and a spring-pressed member having a cam-face to engage with said weather-strip and to press it out of said predetermined position and into a position for closing the space between said closure member and the second one of said elements.

2. In a device of the character described, the combination of two vertical elements spaced from one another, a closure member having vertical edges one of which is hinged on one of said elements, the other vertical edge being free and adapted to swing into slightly spaced relation to the second one of said elements, a weather-strip hinged on a vertical axis on the free edge-portion of said closure member and provided with means to yieldingly hold it in spaced relation to the extreme edge, and a spring-pressed member having a cam-face to engage with said weather-strip and to press it out of said spaced relation and into a position for closing the space between said closure member and the second one of said vertical elements.

3. In a device of the character described, the combination of two elements spaced from one another, a closure member hinged on one of said elements and adapted to swing into slightly spaced relation to the second one of said elements, a weather-strip movably secured on said closure-member and provided with means to yieldingly hold it in spaced relation to an adjacent edge of the closure member, a casing in fixed relation to said element on which the closure member is hinged, a member slidable in said casing and having a cam-face to engage with said weather-strip for moving it into a position for covering said adjacent edge and the adjacent edge of said second one of said elements, and spring-means to press said cam-face against said weather-strip, said spring means being within said casing.

HARLEY M. PURDY.
